UNITED STATES PATENT OFFICE.

JOHN C. WILLIAMS, OF KANSAS CITY, MISSOURI.

AIR-COMPRESSOR.

SPECIFICATION forming part of Letters Patent No. 728,149, dated May 12, 1903.

Application filed March 12, 1902. Serial No. 97,929. (No model.)

To all whom it may concern:

Be it known that I, JOHN C. WILLIAMS, a citizen of the United States, residing at Kansas City, in the county of Jackson and State 5 of Missouri, have invented new and useful Improvements in Air-Compressors, of which the following is a specification.

This invention relates to an air-compressor; and the aim and purpose of the same are 10 to provide a simple and effective compressing apparatus adapted to be manually operated, whereby air may be compressed in an expeditious and positive manner through the medium of a minimum amount of applied 15 power.

The invention consists in the construction and arrangement of the several parts, which will be more fully hereinafter described and claimed.

20 In the drawings, Figure 1 is a sectional elevation of an air-compressor embodying the features of the invention. Fig. 2 is a top plan view of the same. Fig. 3 is a horizontal section taken in the plane of the line 3-3, Fig. 25 1. Fig. 4 is a detail transverse section, on an enlarged scale, of one of the compressing-tubes and the tubular plunger coöperating therewith. Fig. 5 is a detail view, on an enlarged scale, showing the knife-edge fulcrum 30 or the fulcrum-arm.

Similar numerals of reference are employed to indicate corresponding parts in the several views.

The numeral 1 designates a cylinder of any 35 capacity and adapted to be supplied with means for conveying the compressed air therefrom to a distance for use for various purposes. The cylinder will be supported or held in stable position by a suitable frame or 40 base structure, and at a point centrally thereof uprights 2 rise from opposite sides and reduce toward their upper ends, where they are connected by a transversely-extending V-shaped fulcrum-bar 3 to provide an upper 45 reduced or knife edge 4. A fulcrum-pin or trunnion-rod 5 is movably mounted in bearings 6, held on the bar 3 at the center of the latter, and has an under concave recess 7 extending the full length thereof and in continu-

ous engagement with the edge 4 of said bar 3. 50 The pin or rod 5 is secured to or forms a part of a fulcrum-arm 8, having terminal incurved extremities and formed with a groove 9, in which a projecting cable 10 is mounted, the extremities of the said cable projecting 55 below the terminals of the arm 8 any suitable distance. The cable 10 may be replaced by any analogous device, such as a chain, and is free to move over the arm 8.

Rising from the cylinder 1 at equal distances from the plane of the uprights 2 and in longitudinal alinement are a series of angle-guides 11, four of said guides being disposed in operative relation in each series. Mounted in each series of the angle-guides 65 to have unretarded vertical reciprocation is a weight 12, and to the centers of the upper ends of the said weight the terminals of the cable 10 are secured. The uprights 2 below the bar 3 are also connected by a transverse 70 rock-shaft 13, and thereon is applied a rock-lever 14 of arcuate form and having the terminals 15 downturned and movably attached by links 16 to the upper ends of the weights 12. Also secured to the rock-shaft are oscillating levers 17 in the form of inverted arcuate castings or other metallic formations and having upwardly-extending centrally-attaching arms 18, secured by curved braces 19 to the main body of the levers 17, the 75 latter being extended outwardly in opposite directions beyond the plane of the angle-guides 11 for convenience in engagement by an operator. The ends of the levers are connected by hand-bars 20, and it is obvious that 80 in the operation of the shaft 13 an operator can grasp each hand-bar and actuate the said shaft by an alternate swinging movement of the levers and a consequent alternate rise and fall of the opposite weights through the 85 medium of the rock-arm 14, which is secured to said rock-shaft. The levers 17 are applied to the rock-shaft on opposite sides of the series of angle-guides 11, and in view of the extension or increased length of the levers 17 90 in arcuate planes their amplitude of movement is considerable.

Inside the plane of each series of angle-

guides 11 are a plurality of compressing-tubes 21, which have their lower terminals extending through the upper portion of the cylinder 1 and supplied with downwardly-opening 5 spring-closed valves 23. At the points where the tubes 22 pass through the cylinder 1 seats 24 are formed with apertures 25 therethrough, and directly under these seats the valves 23 are located. Within the compressing-tubes 10 22 a series of tubular plungers 26 have operation and have lower heads 27 closely fitting against the inner sides of the said tubes. The plungers normally project above the upper ends of the tubes 22, the latter fitting 15 closely against said plungers and the upper ends of the tubes having air-entrance openings 28. The heads 27 of the plungers are also supplied with downwardly-opening spring-closed valves 29, and it will be understood 20 that at points where desired suitable packing material will be introduced to insure the formation of air-tight joints between the plungers and the tubes. The tubes 26 are normally held elevated and projected equally 25 above the compressing-tubes 22 by coil-springs 30 in the latter and terminally bearing respectively on the seats 24 and against the heads 27.

The operation of the device is as follows: 30 One or more operators can grasp the hand-bars 20 of the levers 17 and impart an oscillating movement to the united levers, and consequently actuate the rock-shaft 13, which in turn similarly operates the rock-arm 14 so as 35 to alternately elevate and depress the opposite ends of the latter. This alternate elevation and depression of the opposite ends of the rock-arm similarly actuates the weights 12, and as the latter are forced downwardly 40 they press upon the upper ends of the tubular plungers 26 and force the same downwardly into the compressing-tubes 22, and thereby drive the air in the said compressing-tubes through the valves 23, which will be 45 opened by the downward movement of the plungers into the cylinder 1. All the plungers are simultaneously depressed, and multiple charges of air are thus driven into the cylinder. As the operation becomes successive 50 the cylinder 1 will become rapidly filled and the air therein compressed under considerable tension or stress, particularly in view of the independent sets of the compressing-tubes, with which the individual weights and 55 series of tubular plungers coöperate. Each weight is caused to rise directly with the corresponding upward movement of the link 16 attached thereto in advance of the upward movement of the plungers 26, which are in- 60 dependent of the said weights, the plungers being forced upwardly by the springs 30, and at which time the air flows into the plungers, and though the interval between the rise of the plungers and the weights is re- 65 duced to a minimum and is controllable by

the tension of the springs 30 such interval will be sufficient to permit the surrounding air to inflow into the plungers and be forced into the compressing-tubes during the descent of the plungers and weight. In some 70 instances it may be desired to provide intakes for the compressing-tubes; but as this is an obvious expedient in air-compressors it has not been shown in the drawings. The fulcrum-arm 8 provides means for effectively 75 suspending the weights and moves in consonance with said weights, and through the medium of the reduced or knife edge 4 frictional obstruction to the operation of the arm 8 is also materially reduced, and, in fact, 80 friction is almost entirely absent. By the use of the arm 8 the weights are removed from direct support by the rock-arm 14, and as the said weights counterbalance each other in their operation the wear and tear on the 85 rock-arm, as well as the remaining operating devices, is reduced to a minimum, and, as before stated, the actuating power is similarly reduced.

It is proposed to employ the improved compressing mechanism for compressing air at a materially less expense than is usually the case where motive power, such as steam, is used, and to arrive at a practical compressing operation through the medium of manual 90 power. The air-compressor is particularly adapted for use at such planes of elevation where it is impracticable to obtain fuel or operate a steam or other motive mechanism, and to suit different conditions it is proposed 95 to change the form, proportions, size, dimensions, and minor details without departing from the principle of the invention.

Having thus fully described the invention, what is claimed as new is—

1. An air-compressor comprising a storage-cylinder, a plurality of air-compressing tubes connected to the cylinder, plungers coöperating with and movable through the upper ends of said compressing-tubes, said plungers having upper open ends, counterbalancing-weights operating in connection with the plungers and contacting with the upper open ends of the latter, and operating mechanism attached to the said weights. 115

2. In an air-compressor, the combination of a storage-cylinder, a plurality of air-compressing tubes communicating with said cylinder and arranged in opposite independent series, plungers coöperating with and movable 120 through the upper ends of said compressing-tubes, counterbalancing-weights located directly over and adapted to engage the upper open ends of the plungers for forcing the latter into the compressing-tubes, manually-operated means for actuating the weights, and suspending means for the said weights. 125

3. In an air-compressor, the combination of a storage-cylinder, a plurality of compressing-tubes communicating with said cylinder 130

and arranged in independent series, tubular plungers operating in and movable through the upper ends of said compressing-cylinders and adapted to be automatically returned to normal position, independent suspending-weights to engage the upper ends of the plungers and force them into the compressing-tubes, and manually-operated mechanism co-

operating with the weights to clear the latter from the plungers.

In testimony whereof I affix my signature in presence of two witnesses.

JOHN C. WILLIAMS.
